UNITED STATES PATENT OFFICE.

FRANCIS H. WHOMES, OF LOS ANGELES, CALIFORNIA.

PROTECTOR FOR CIGARS.

No. 823,014.

Specification of Letters Patent.

Patented June 12, 1906.

Application filed December 31, 1902. Serial No. 137,302.

To all whom it may concern:

Be it known that I, FRANCIS H. WHOMES, a citizen of the United States, residing at Los Angeles, in the county of Los Angeles and 5 State of California, have invented a new and useful Protector for Cigars, of which the following is a specification.

My invention relates to a simple device for covering the tip of a cigar for preventing the 10 evaporation of moisture from the cigar and also acting as a protector or guard to prevent the chipping off of the end of the cigar and unrolling the wrapper, which is frequently caused when the cigars are carried loosely in 15 the pocket.

Referring to the drawings, Figure I is a view of a cigar which is rolled with a blunt or "square" end and which is provided with the protector. Fig. II is a view of a cigar of 20 the "Perfecto" or small-end type which is provided with the protector. Fig. III is a perspective view showing one form of the cap or protector. Fig. IV is a perspective view of another form of protector. Fig. V is 25 a perspective view of still another form of protector with a portion of the cigar shown in dotted lines.

The invention comprises a cap or thimble which may desirably be constructed of a thin, 30 light, and impervious substance—such, for instance, as rubber. The cap might be constructed of oiled paper or other material rendered waterproof by some approved process. Where the cap is made of rubber or other elastic material, as illustrated in Figs. I and III, 35 in which 1 designates the body of the cap, the upper rim of the cap should preferably have a selvage 2. This selvage may be simply a slight ridge formed by doubling over the edge 40 of the material and then pressing. The cap being formed of flexible material is adapted to conform closely to slight inequalities of the surface of the cigar, as at the edge of a layer, when pressed against it by an elastic band, 45 so that air is not apt to enter under the band. This elastic band may be constituted by a selvage of a cap of flexible and elastic material turned over on itself, as indicated in Fig. III, or it may be constituted by a separate 50 band of elastic material, as indicated in Fig. V.

The rubber composing the cap may be very thin and light in weight, so that the cost of the same will be extremely small.

In use the cap may be slipped over the tip of 55 the cigar and placed in position, as shown in Fig. I, the elasticity of the cap causing it to

closely hug the end of the cigar sufficiently to prevent it from accidentally being removed. The selvage serves to reinforce the edge of the cap and gives the cap greater strength 60 and elasticity at that point and also serves to prevent the cap from splitting or tearing. It also affords a slight ridge, which facilitates the removal of the cap when desired by the smoker.

It is well known that cigars rolled with blunt tip are constructed at much less expense than cigars which are rolled as Perfectos, or cigars having small ends, as the rolling of these require an expert hand, and 70 one of the main reasons for rolling cigars of the Perfecto style is that when cigars are rolled, as shown in Fig. I, of the blunt tip, the moisture is allowed to evaporate, whereas the Perfecto cigar has such a small tip that the 75 evaporation is not so great as in the cigar with the blunt tip. It is obvious that by the use of the protector, which forms the subject-matter of the present invention, the cigars may be rolled with the blunt tip, as shown 80 in Fig. I, and the evaporation prevented.

In Fig. IV is shown another way of constructing the cap in which the form of the cap may be that of a truncated cone. This cap may, if desired, be constructed of ordinary 85 paper, or it may be constructed of rubber or oiled paper or paper waterproofed by any approved means, or, in fact, of any desirable material. This cap may be used on Perfectos. The advantage of making the cap conical is 90 that when the material used in the construction of the cap is of paper or stiff material the conical shape of the cap will allow it to be pressed on the conical tip of the cigar, so as to tightly wedge it on.

Fig. V illustrates another form of construction of the cap, in which 1 designates the cap and 3 designates a rubber or other elastic band. In this form the cap 1 may be of oiled paper and may be held in place over the 100 end of the cigar by means of a rubber band 3.

It is obvious that this device furnishes a very convenient medium for carrying the name of the cigar or other advertisement. The character of the advertising matter on 105 the tip may be analogous to that placed on the paper bands which are so commonly used as girdles around the center portion of many cigars at the present time.

The cap may be provided with various embossed or lithographed designs applied with various colors, &c., so that the cap when it is

in place on the tip of the cigar will present a very handsome appearance.

It is obvious that the tips being constructed of such inexpensive material they are not designed necessarily to be used more than once, and the smoker will strip off the cap and throw it away. By reason of the cap covering the end of the cigar the natural moisture of the cigar will be retained, and thus such caution need not be used in handling the cigars as at present required in providing moisture-proof cases in which sponges and water, &c., are kept to keep the cigars moist and in the employment of tin-foil 5 wrappers around the cigars, &c. It is well known that the tip of the cigar is the part that is most often injured and that it easily chips and breaks and the wrapper is often accidentally unrolled or loosened owing to 10 cracking or chipping of the leaf at the tip. The cap forms a perfect protection against 15 this.

I am aware that cigars have been protected against smashing or being crushed by rigid 20 caps of metal or sufficiently thick celluloid or built-up paper material and that such caps may to a slight extent prevent evaporation 25 of moisture from the cigar; but it is well known that cigars keep their flavor much better when the air is excluded from them, especially at the open tip, and so far as known 30 the best method now in use is the tin-foil wrapping; but my cap being of very thin, elastic, and flexible material when placed over 35 the open end of the cigar hugs every covered part tightly like a skin, so that air is absolutely excluded from the end and the moisture in the cigar cannot escape.

I am also aware that cigars have been 40 painted on their ends to retain moisture; but such expedient is a process treatment in the manufacture of the cigar, is a permanent part of the cigar, and is not obviously herein claimed by me, as my invention comprehends an article of manufacture which is a 45 cap adapted to be put on or taken off a cigar at pleasure, one of its distinguishing features being that it may be removed by the smoker just prior to lighting his cigar, and after the 50 cigar has been partially smoked and the

ashes knocked off the cap may be replaced to cover the burned end, so that the cigar may be carried in the pocket until the smoker again wishes to light up. This cap being very elastic accommodates itself to the increased size of the burned end and to all irregularities in shape and not only prevents the burned end from soiling the pocket, but also by thoroughly covering and tightly fitting the end prevents the nauseating odor 55 from being smelled or from permeating the clothes.

Having described my invention, what I claim, and desire to secure by Letters Patent of the United States, is—

1. The combination with a cigar of a removable cap covering the end thereof, said cap being cup-shaped and composed of a light, thin, elastic, impervious material.

2. The combination with a cigar of a cup-shaped cap covering the end thereof composed of thin rubber, said cap hugging the end of the cigar like a skin but being easily removable when it is desired to light the end of the cigar.

3. The combination with a cigar of a removable cap covering the end thereof, said cap being cup-shaped and composed of a light, thin, elastic, impervious material, the rim of the cap having an external selvage to 75 strengthen the edge and prevent splitting of the material and also affording means which may readily be caught by the fingers in removing the cap.

4. A protector for cigars provided with a cap and a thin, elastic rubber band to fit the cigar, the same being very elastic to accommodate itself to the increased size of the burned end and to all the irregularities in shape.

In testimony whereof I have signed my name to this specification, in the presence of two subscribing witnesses, at Los Angeles, in the county of Los Angeles and State of California, this 24th day of December, 1902.

FRANCIS H. WHOMES.
